Attorney, Agent, or Firm—Jones & Askew, LLP*[57] **CLAIM**

The ornamental design for a bottle, as shown and described.

DESCRIPTION

FIG. 1 is a perspective view of my new bottle;

FIG. 2 is a top plan view thereof;

FIG. 3 is a bottom plan view thereof;

FIG. 4 is a front view thereof; and,

FIG. 5 is a right side elevation view thereof.

The broken lines showing the bottle neck and base are for illustrative purposes only and do not form part of the claimed design.

The portions of the bottle that are not shown in the drawings do not form a part of the claimed design.
